UNITED STATES PATENT OFFICE

GODFREY DALKOWITZ, OF NEW YORK, N. Y., ASSIGNOR TO THE LOX SEAL CORPORATION, OF BROOKLYN, NEW YORK, A CORPORATION OF NEW YORK

PILE-WIRE HEAD

Application filed October 11, 1926. Serial No. 140,773.

My present invention relates to pile wires for looms, and has particular reference to heads for holding the pile wires.

The manner in which the manufacture of pile fabrics subjects the connection between the pile wire and its head to stresses makes it essential that the pile wire heads or holders grip the wires firmly and retain their grip during the reciprocating motion of the wires and their accompanying stresses and strains.

It is among the objects of the present invention to provide a holder of this character. More particularly, it is an object of the invention to provide a holder and a connection 15 thereof to the wire which will be of extremely simple construction and therefore inexpensive to manufacture and which will not adversely affect the weaving operation.

In accordance with the requirements of 20 looms, I provide a holder or head which is substantially flat, and it is a feature of my invention to provide a longitudinal bore therein, into which the wire may be inserted, and in which the wire may thereupon be 25 treated so as to secure it within the holder.

More particularly, a feature of my invention lies in providing a transverse bore in communication with the longitudinal bore, thereby rendering a portion of the wire accessible 30 for treatment through said transverse bore.

In one of the embodiments which I have herein illustrated, and which I shall herein-after describe more fully, the holder or head 35 comprises a laminated or multiple-ply structure wherein spaced complementary stampings are adapted to receive the wire therein-between; and wherein a spacing member cooperates with these stampings in a manner 40 which provides the bores referred to.

In another embodiment herein illustrated, the longitudinal bore is produced by providing a groove in an edge of a substantially flat member and in thereupon blocking a portion 45 of the groove by an insert.

In a preferred embodiment, the transverse bore is so positioned with respect to the completed longitudinal bore that the inner end of the wire is rendered accessible for the purposes 50 specified. Thus, in one method of car-

rying out my invention, the spacing member or intermediate lamination is provided with a slit which is so disposed in relation to registering openings in the outside laminations that the end of the pile wire is brought into 55 registry with these registering openings. In another embodiment, the groove insert which serves to provide the longitudinal bore by means of its disposition in the groove of a flat member, is provided with an end or 60 hooked portion which serves to define the inner limit of the bore; and by defining this limit at a proper predetermined position, the end of the pile wire may similarly be brought into registry with the transverse bore re- 65 ferred to.

In general, it is a feature of my invention to provide a pile wire and holder wherein the former is disposed within a longitudinal bore or sheath, and wherein a portion of the wire 70 is treated so as to deflect it out of the true axis of the bore, thereby locking it in position. This deflection is made to occur at a point where a transverse bore is provided, the transverse bore communicating with the lon- 75 gitudinal bore.

For the attainment of the foregoing objects and such other objects as may herein-after appear or be pointed out, I have illustrated several embodiments of my invention 80 in the accompanying drawings in which

Fig. 1 is an unassembled view of a laminated type of holder, showing the relative disposition of the elements of the holder and of the pile wire to be held;

Fig. 2 is an elevational view of a pile wire associated with a holder of this character, a portion of this figure being broken away for the sake of clearness;

Fig. 3 is a cross-sectional view taken along the line 3-3 of Fig. 2;

Fig. 4 is a fragmentary perspective view, showing a modification of the holder in unassembled condition;

Fig. 5 is a perspective view, showing the association of a wire with a holder of the type shown in Fig. 4;

Fig. 6 is a cross-sectional view taken along the line 6-6 of Fig. 5;

Fig. 7 is a view similar to Fig. 2, showing a further modification;

Fig. 8 is a cross-sectional view taken along the line 8—8 of Fig. 7; and

Fig. 9 is a perspective view of an insert of the character used in the construction of Figures 7 and 8.

Referring to the drawings, and particularly to Figures 1, 2, and 3, it will be observed that I have shown a pile wire 10 and a three-ply structure for holding the wire in position. This structure comprises superposed stampings 11, 12, and 13, these stampings being substantially flat, and preferably entirely flat, as illustrated; they are preferably made of metal, whereby they may be assembled in superposed positions and attached together by any suitable means such as spot-welding.

I have shown these stampings provided with openings and configurations which are of importance in the matter of associating the assembled holder with the loom. In connection with the present invention, the important structural features are the registering openings 14 and 15 provided in the stampings 11 and 13, and the slit or cut-out portion 16 provided in the stamping 12. The latter is preferably made of a thickness substantially equal to the thickness of the wire 10, and the slit 16 is preferable of a width substantially identical with the width of the wire 10, whereby the latter may be disposed within the slit in a snug manner. The slit 16 is so disposed, and is of such a length, that the end of the wire 10 will be brought into registry with the openings 14 and 15, when it is properly and completely inserted into the slit 16.

It will be understood that the wire is not inserted into the slit 16 until the stampings 11, 12, and 13 have been properly assembled. They are assembled by superposing them successively, as shown in Fig. 1, and it will be observed that their mutual association will provide a longitudinal composite sheath or bore whose sides are constituted by the inner surfaces of the stampings 11 and 13, and whose other sides are constituted by the opposite inner surfaces of the slit 16. The inner end of the latter is preferably enlarged in a manner whereby the assembled device will embody a transverse bore communicating with the inner end of the longitudinal bore, this transverse bore being constituted of the registering openings 14 and 15, and the enlarged inner end 17 of the slit 16. It will now be observed that after the holder has been assembled, the wire 10 may be inserted into the bore which has been provided, the inner end 18 of the wire being limited by the end of the slit 16, and the end portion of the wire adjacent to the end 18 being positioned in registry with the transverse bore so that it is rendered accessible for subsequent treatment.

Reference to Figures 2 and 3 will indicate a preferred method of treatment for locking the wire in position. The transverse bore is preferably made circular in cross-section, its diameter being greater than either of the dimensions of the rectangular longitudinal bore. In this manner, it will be observed that the end of the wire 10 may be expanded in any transverse direction, thereby providing a head which will prevent withdrawal of the wire through the longitudinal bore. Although the method of treatment is more or less optional, I prefer to utilize the transverse bore for the purpose of applying an instrumentality such as a punch or die, to the end of the wire 10, and I expand this end in all directions. In Fig. 3, I have shown the effect of applying a punch, and it will be observed that a kink is provided which deflects the end of the wire out of the true axis of the longitudinal bore, and in a direction which is axial with respect to the transverse bore. This deflection is accompanied by a flattening of the metal which serves to expand the wire in the other transverse direction, thereby increasing the effectiveness of the expansion. After the pile wire has been treated in this manner, I prefer to fill up the transverse bore by the insertion of solder thereinto, and it will be observed that this application of solder will still further enhance the security of the grip.

It will be thus seen that in its broadest aspect this embodiment of my invention comprises spaced complementary stampings 11 and 13, and a spacing member 12 which serves not only to properly position the other two stampings but also to guide the pile wire into proper position with respect to the openings 14 and 15.

In Figs. 4, 5, and 6, I have illustrated another method of producing the longitudinal and transverse bores. In this construction, a substantially flat stamping 19, having a thickness substantially equivalent to the combined thickness of the laminations of Fig. 1, is provided with a longitudinal groove 20 extending inwardly from a longitudinal edge 21. This groove may be provided in any suitable or desired manner, and I prefer to produce the groove by milling. The depth of the groove is made greater than the width of the pile wire, but the width of the groove is made substantially equal to the thickness of the pile wire. After the groove has been formed, I insert thereinto a strip 22 having a depth less than the depth of the groove and having a length substantially equal to that of the groove. This strip or insert 22 is fixedly positioned along the outer portion of the groove so as to close up this outer portion and provide a longitudinal bore thereunder of suitable dimensions for the reception of the pile wire. In other words, the difference between the depth of the groove 20 and the

depth of the insert 22 is substantially equal to the width of the pile wire.

Openings 23 and 24 are provided in the main stamping 19, these openings registering with each other in the same manner as the openings 14 and 15 register, and permitting access to a portion of the pile wire after it has been inserted into the longitudinal bore. In this embodiment, and in the embodiment 10 presently to be described, these openings have been shown as of an elliptical nature, although it will be understood that their particular configuration is more or less optional.

In Fig. 6 I have illustrated a preferred 15 method of treating a portion of the pile wire after it has been inserted into the bore. By the application of a punch or die through the transverse bore constituted of the openings 23 and 24, the accessible portion of the wire 20 is deflected out of the axis of the longitudinal bore and in a direction which is substantially axial with respect to the transverse bore. This deflection again provides a kink which serves to hold the wire in position, and the kink is accompanied by an expansion 25 in the other transverse direction, this expansion being permitted by the elongation of the openings 23 and 24, and being effective in increasing the security with which the wire 30 is held. Here too, the openings 23 and 24 may be subsequently filled up with solder, thereby increasing the hold upon the wire and producing a neat and workmanlike effect.

In a construction having a general nature 35 such as that illustrated in Figures 4, 5, and 6, I prefer to provide the insert 22 in the form of a hooked insert 25 (Fig. 9), for a purpose presently to be described. Reference to Figures 7, 8, and 9, will illustrate an embodiment 40 wherein this hooked insert effects the carrying out of a feature of my invention. The insert is provided with a hook or inner portion 26 whose outside surface 27 conforms with the end surface of the milled groove, and 45 whose depth is substantially equal to that of the groove. The length of the hook 26 is properly co-related with the position of the openings 23' and 24' so that a shoulder 28 is provided which registers with the innermost surfaces of these transverse openings. The transverse bore is herein constituted of the openings 23', 24', and the shoulder 28, and the latter constitutes an inner limit for the longitudinal bore which has been 55 provided. This inner limit serves to position the end of the pile wire 10 in registry with the transverse bore, thereby permitting the end to be treated in a manner much the same as the end was treated in Figures 1, 2, and 3.

In connection with the last described embodiment, it will be obvious that the hook 26 may be dispensed with entirely, and the openings 23' and 24' may be suitably positioned 60 to bring the transverse bore into communication with the end portion of the longitudinal

bore. In a construction of this character, the groove may have to be provided otherwise than by milling, so that the circular end of the groove may be avoided.

It will thus be observed that I have provided a holder which is particularly efficient from the standpoint of gripping the pile wire, and which is of extreme simplicity from the standpoint of manufacture. It will be obvious that many changes in the details herein described and illustrated for the purpose of explaining the nature of my invention may be made by those skilled in the art without departing from the spirit and scope of the invention as expressed in the appended claims. It is therefore intended that these details be interpreted as illustrative and not in a limiting sense.

Having thus described my invention and illustrated its use, what I claim as new and desire to secure by Letters Patent is—

1. A pile wire head comprising a flat stamping having a groove in an edge thereof and a groove insert blocking the end of the groove open to said edge to provide a recess thereunder for the reception of a pile wire.

2. A pile wire holder comprising a substantially flat structure having a longitudinal groove in an edge thereof, having also a transverse bore communicating with said groove, and a groove insert carried within the outer portion of the groove to constitute a longitudinal bore thereunder, said insert having an enlarged inner end providing a shoulder which registers with the transverse bore and provides an end stop for the inner end of a pile wire inserted into the longitudinal bore.

3. A flat pile wire head comprising spaced side walls adapted to sandwich a pile wire therebetween, a body having a thickness equal to the thickness of said walls and space and having its outer portions integral with said walls, and an insert interposed between said walls and having an edge which overlies the edge of the sandwiched pile wire.

4. A flat pile wire head comprising spaced side walls adapted to sandwich a pile wire therebetween, said walls having registering openings, a body having a thickness equal to the total of said walls and space and having its outer portions integral with said walls, and an insert interposed between said walls and having an edge which overlies the edge of the sandwiched pile wire and guides the latter into predetermined position with its sandwiched end aligned with said openings.

5. A pile wire head comprising a flat element with a main portion of total head thickness and an integral split portion providing spaced side walls, said walls having registering openings therethrough, and a shouldered insert interposed between said walls and so constructed as to provide a longitudinal bore thereunder and between said walls for the accommodation of a pile wire, said shoulder

being positioned to limit the insertion of the pile wire into said bore so that the inner end portion of the pile wire will be aligned with said openings.

5 6. A pile wire head comprising a flat stamping having a groove in an edge thereof, the opposite walls of said groove being provided with registering openings, and a groove insert blocking the end of the groove open to said
10 edge and provided with an inner edge which guides a pile wire into the recess provided beneath the insert with the inner end portion of the pile wire aligned with said openings.

7. A pile wire head comprising a flat stamping having a groove in an edge thereof, and a groove insert blocking the end of the groove open to said edge through its total length to provide a recess thereunder for the reception of a pile wire, said insert being constructed
15 to block the entire depth of groove at the inner end thereof so as to limit the inward movement of the pile wire into said recess.

8. A flat head having a longitudinal groove from its forward end along a portion of one side edge extending in depth inwardly parallel to the width of the head, a pile wire having an end seated in the groove and means fastening the pile wire end to place on its seat.

20 80 In testimony whereof, I have hereunto signed my name.

GODFREY DALKOWITZ.
